**COMBINED CUTTER AND TOOL FOR REMOVING
PLUGS OR APERTURED CAPS**

James F. Campbell, Box 842, Grand Junction, Colo.

Filed June 2, 1961, Ser. No. 65,432

Term of patent 14 years

(Cl. D93—4)

FIG. 1 is a side elevational view of a combined cutter and tool for removing plugs or apertured caps embodying my new design;

FIG. 2 is a top plan view thereof;

FIG. 3 is a front elevational view thereof;

FIG. 4 is a sectional view taken along line 4—4 of FIG. 1; and

FIG. 5 is a sectional view taken along line 5—5 of FIG. 1.

The dominant features of my design reside in the portions shown in full lines.

I claim:

The ornamental design for a combined cutter and tool for removing plugs or apertured caps, substantially as shown and described.
